Primary Examiner — John Windmuller(74) *Attorney, Agent, or Firm* — Patterson Thuente Pedersen, P.A.(57) **CLAIM**

I claim the ornamental design for an IDM dual-band miniature antenna, as shown and described.

DESCRIPTION

FIG. 1 is a perspective view of an IDM dual-band miniature antenna according to the invention.

FIG. 2 is a front elevation view of the IDM dual-band miniature antenna depicted in FIG. 1.

FIG. 3 is a rear elevation view of the IDM dual-band miniature antenna depicted in FIG. 1.

FIG. 4 is a top plan view of the IDM dual-band miniature antenna depicted in FIG. 1.

FIG. 5 is a bottom plan view of the IDM dual-band miniature antenna depicted in FIG. 1; and,

FIG. 6 is a side elevation view of the IDM dual-band miniature antenna depicted in FIG. 1.

The broken lines illustrate portions of the IDM dual-band miniature antenna which form no part of the claimed invention.
